Patent drawings will be shown in the order indicated. The first drawing is a front view of the seat, the second is a side view, the third is a bottom plan view, the fourth is a side detail view of one of the side frame members, the fifth is a front view of the back portion of the chair, the sixth is a side detail view of the back portion of the chair, the seventh is an enlarged detail view of the arm rest and frame, the eighth is an enlarged detail view of one of the side frame members, the ninth is an enlarged detail view of the hinge structure of the back portion of the chair, and the tenth is a side view of the lower portion of the chair frame.

UNITED STATES PATENT OFFICE

2,518,860

AIRCRAFT PASSENGER CHAIR

Max T. Blue, Wichita, Kans.

Application October 31, 1946, Serial No. 706,818

3 Claims. (Cl. 155—194)

1. A seat for an aircraft passenger seat, comprising

My invention relates to an improvement in aircraft passenger seats. The object of my invention is to provide a seat of the kind mentioned that is strong and light in weight, one that is comfortable and has spring supported upholstering in both the seat and back, one in which the back is easily adjustable forward or backward, and one in which the seat may be easily removed.

A still further object is to provide a seat of the kind mentioned which, while being designed for passenger air use, can be easily converted for ordinary domestic use.

A still further object is to provide a seat of the kind mentioned that is fast, easy and inexpensive to build and one that is neat and has a pleasing appearance. These and other objects will be more fully described and explained as this description progresses.

Now referring to the accompanying drawings in which similar numerals of reference designate the same parts throughout the several figures of the drawings;

Fig. 1 is a front view of a single seat in which the above mentioned objects are included.

Fig. 2 is a front view of a double seat in which the above mentioned objects are included.

Fig. 3 is a side view of the seats shown in Figures 1 and 2.

Fig. 4 is a bottom plan view of the seat shown in Fig. 1. The construction shown in Fig. 4 is common to both the seats shown in Fig. 1 and Fig. 2.

Fig. 5 is a sectional view through the seat, the view being taken along the line V—V in Fig. 3 and looking in the direction of the arrows. The upholstering has been removed for convenience of illustration.

Fig. 6 is a side detail of the back frame of the chair.

Fig. 7 is an enlarged detail sectional view through the arm rest and frame therefor, the view being taken along the line VII—VII in Fig. 3 and looking in the direction of the arrows.

Fig. 8 is an enlarged detail side view of a portion of one of the side frame members, parts being broken away for convenience of illustration.

Fig. 9 is an enlarged sectional detail view through the hinge structure of the back portion of the chair, the view being taken along the line IX—IX in Fig. 5 and looking in the direction of the arrows.

Fig. 10 is a side view of the lower portion of the frame of the chair and illustrating how the chair

can be converted into a rocking chair for domestic use.

Fig. 11 is a detail sectional view of the lower portion of the chair frame, the view being taken along the line XI—XI in Fig. 10 and looking in the direction of the arrows.

Fig. 12 is a detail sectional view through a portion of the chair seat, the view being taken along the line XII—XII in Fig. 4 and looking in the direction of the arrows.

Fig. 13 is a view, the same as Fig. 3 except that one of the supporting elements of the chair is raised to rest on a heating duct existant in the aircraft.

In the drawings the single chair, see Figures 1, 3, 4 and 5 is shown as having a pair of side frame elements 15 and 16 that are duplicates in shape and are made preferably of tubular material and of which each has a straight horizontal base portion *a* that is bent with rounded corners to form vertically and upwardly extending front leg *b* and rear leg *c* elements, the front leg *b* curving rearwardly and thence curving downwardly to form an arm rest support *d* and then curving in a still more downwardly direction and merging into the upper end of the rear leg *c* as shown more clearly in Fig. 3. As shown in Fig. 2, the frames 15 and 16 are spaced double distance apart and a third frame 17 that is a duplicate in shape of the frames 15 and 16 is positioned between the frames 15 and 16 which frames provide a frame work for the support of the double chair as shown in Fig. 2. The base portion *a* of each frame 15, 16 and 17 is provided with a pair of inwardly directed lug elements 18 and 19, each of which has a hole 20 therein, through which bolts may be passed to fasten the chair to the floor of the aircraft; or if the chair is to be used as a rocking chair, a rocker 21 may be placed under the lugs 18 and 19 and rigidly bolted thereto by means of bolts 22 that are passed through the lug holes 20 and are preferably threaded into the rocker 21, as shown in Figs. 10 and 11.

The front legs *b* of the frames 15 and 16, as shown in Figs. 1, 4, 10 and 11 are rigidly held in their spaced apart and parallel position by means of a tubular element 23, the ends of which are rigidly welded to their respective front leg element *b*. The tubular element 23 is positioned at the proper height to support the front of the seat frame of the chair as will later be described.

The rear legs *c* of the frames 15 and 16 are rigidly held in their spaced apart and parallel position by means of a tubular element 24, the ends

55

of which are rigidly attached, preferably welded, to the legs *c*.

In both frames 15 and 16 is a tubular support element *e* that is positioned between the legs *b* and *c*, and slopes downwardly from front to rear, and the ends of the support element *e* are each welded to their respective leg *b* and *c*.

A tubular cross support element *f* is positioned between the two supports *e* in the two frames 15 and 16 and a little in front of the cross element 24, and the ends of the cross support element *f* are each welded to their respective support element.

The chair is provided with a seat element *g* that has a tubular rectangular shaped base or frame 25, the rear corners of which are inset or notched inwardly as at 26 to fit around the mounting mechanism of the back of the chair which will later be described. A series of parallelly positioned and spaced apart, arched zig-zag shaped spring steel wire elements 27 are positioned between the front and rear members of the frame 25 and the ends of the spring members 27 are welded to their adjacent front or rear member of the seat frame 25. A spring member 28 that is of the same type as the spring members 27 is positioned about midway between the front and rear members of the seat frame 25 and the ends of the spring member 28 are welded to their adjacent side member of the seat frame 25. The spring member 28 serves as a further and additional seat support to the springs 27. A thick padding 29, cotton, felt, sponge rubber, or a combination of these elements is positioned on top of the spring support 27-28 and an upholstering material 30 is placed thereover and brought down around the sides and ends of the seat and wrapped under and around the side and end members of the seat frame 25 and sewed to form the upholstered seat cover 30. The seat *g* having thus been made is placed on and is supported by the tubular chair frame members 23 and *f*, and clips 31 are rigidly fastened by bolts 32 to the tubular side members of the seat frame 25 and pass around the chair frame members 23 and *f* to rigidly hold the seat *g* in the chair frame.

The chair arm members *d* are provided with upholstered arm rests *h* that are constructed as follows: The arm rest *h* has a curved channel shaped member 33 that is formed to fit on and be received by the member *d* of the chair frame 15, 16 and 17. A padding 34, preferably made of sponge rubber, is fitted between, over and around the upturned legs of the curved channel 33, and an upholstering material 30a is placed over the top and sides of the padding 34 and under the channel 33 which is then laid and fitted on the frame member *d*, and screws 35 are passed through the frame member *d* and threaded into the channel 33 to solidly hold the arm rest *h* on the frame member *d*.

The chair is provided with an adjustable back *i* having an inverted U-shaped frame *j* having a tubular top cross member 33a and tubular side members 34 and 35, the lower ends of which curve forwardly as at 36 and the ends thereof fit between pairs of upwardly projecting earlike elements 37 and 38, the lower ends of which are welded to the frame elements *e*, and a bolt 39 is passed through the ears 37 and 38 and the lower ends of the legs 34 and 35 to form a pivotal mounting of the back *j* on the chair. Helical springs 40 and 41 are positioned, one around each of the bolts 39 with one end of each spring 40 and 41 hooked around the cross frame member *j* of

the chair and the other ends of the springs 40 and 41 being hooked around their respective leg members 34 and 35, the springs 40 and 41 being so tensioned as to move or urge the forward rocking movement of the back *j* about the pivotal bolts 39.

A cross frame member 42 is positioned between the leg members 34 and 35 at a point just above the curve 36 and the ends of the cross member 42 are each welded to their respective leg members 34 and 35. The chair back is provided with a second inverted U-shaped frame *k* having a top cross member 43 and downwardly extending leg elements 44 and 45, the lower ends of which curve as at 46 and the ends thereof are welded to the legs 34 and 35 of the frame *j* at approximately the same places as the ends of the cross member 42 are welded to the legs 34 and 35. The frame *k* is spaced away from and is held in parallelism with the frame *j* by spacer tubes 47, the ends of which are welded to their respective elements of the two frames *j* and *k* as shown. Also a cross tubular member 48 is positioned between the upper portions of the frame legs 34 and 35 and is welded to the legs 34 and 35. Vertically positioned frame members 49 and 50, having curved ends such as 51, are positioned between the frame legs 44 and 45 and the ends of the curved portions 51 are welded to the top and bottom cross members 33a and 42 of the frame *j*. The frame *j* is provided with zig-zag formed spring wire back supports 52, the ends of which are welded to the frame cross members 33a and 42 and an intermediate point of the springs 52 is welded to the frame cross member 48, and the springs curve outwardly as illustrated at *m* and *n* between the cross frame members 33a and 42, and 48 and 42.

A curved lever support element 53 is positioned between the legs 34 and 35 of the frame *j* and is welded thereto. A lever bar 54 is pivotally carried by the lever support 53 and one end of a helical spring 56 is connected to the upper end of the lever bar 54 and the other end of the spring is connected to one end portion of the lever support member 53 and is tensioned to urge the lever bar 54 to rock toward a horizontal position.

One end of a pair of lock bars 57 and 58 are pivotally connected, one to each end portion of the lever bar 54. The outer end of the lock bar 57 slidably passes through and projects beyond the frame leg 34, and the outer end of the lock bar 58 slidably passes through and projects beyond the frame leg 35. The rear curved portion *d* of the side chair frames 15 and 16 are provided with a series of holes 59, and the frame 17 is similarly provided with holes 59, in which the outer projecting ends of the lock bars 57 and 58 are receivable to hold the chair back in adjusted reclining position as indicated by the dotted positions shown in Fig. 3.

One end of an operating rod 60 is pivotally connected to the lower end of the cantilever bar 54 and the operating rod 60 extends sideway to and slidably passes through and projects beyond the frame leg 34. The outer end of the operating rod 60 is provided with a finished end such as a head or ball 61 by which the operating lever 60 may be operated as will later be described.

The frame *k* and area bounded thereby is covered with a piece of light weight substantial material 62 such as a heavy canvas, a piece of leather, substantial paper or card board or the like and the edges thereof are wrapped around the frame members and cemented to hold the covering 62 in place on the frame *k*.

The seat back having been constructed and as-

sembled as above described, is provided with a suitable padding, not shown, that is placed over the springs 52 and then an upholstering material 63 is placed over the front, back and edges of the seat back *i*. Upholstery buttons 64 are placed on the upholstery 63 and attached to the cross frame member 48 to improve the appearance of the seat back and form a head rest and back rest portion of the back.

Clips 65 having holes 66, are attached to the frame members *e* of the chair for the purpose of attaching a safety belt thereto as is required in air craft seats.

Many air planes have a heating air duct that is positioned on the floor and next to the wall of the plane in a position such as indicated by the dotted lines 68 in Figures 1 and 3, and in order to set the seat in the plane and get it next to the wall of the plane the side seat frame 15 or 16 as the case may be will have to be shortened in height so that the seat frame 15 or 16 will rest on top of the air duct 67 as indicated by the dotted lines 16x in Fig. 3.

If the chair is to be used as a rocking chair for domestic use, rocker elements 69 may be positioned under the attachment clips 18 and 19 and fastened thereto in the same manner as the chair would ordinarily be fastened to the floor of the plane and the chair thereby becomes a rocking chair.

To adjust the position of the back of the chair, the knob and operating rod 61—60 may be pressed inwardly, whereupon the lever bar 54 is rocked against the pull of the spring 56 whereupon the lever bar 54 will pull the lock bars 57 and 58 inwardly and withdraw the outer ends of the lock bars 57 and 58 from the holes 59 in the frames 15, 16 or 17, whereupon the back *i* may be rocked to any desired position as indicated by the dotted lines *y* in Fig. 3. When the seat back *i* has been rocked to the desired position, the operating rod 61—60 may be released and the spring 56 will rock the lever bar 54 to move the lock bars 57 and 58 outwardly and move the outer ends of the lock bars 57 and 58 into the holes 59 that are in registering position therewith and thereby rigidly hold the seat back *i* in its adjusted position.

Such modifications of my invention may be employed as lie within the scope of the appended claims without departing from the spirit and intention of the invention. Now having fully shown and described my invention, what I claim is:

1. In an aircraft passenger chair of the kind described, said chair having a supporting frame, a seat and a back, said supporting frame being made of light weight tubular material, said supporting frame having duplicate side frames, each of said side frames being made of a single piece of material and having a straight bottom portion, substantially vertical front and rear leg portion, and a curved upper arm rest support portion, and an arm rest, said arm rest being detachably attached to the said arm rest support, said side frames having a support tube, said support tube being positioned between the front and rear legs of the side frames and sloping downwardly from front to rear and being welded to the legs of the side frame, a front and a rear cross tube, said front cross tube being positioned between the front legs of the side frames and welded thereto at the same level as the adjacent point of joinder of the said support tube with the front leg of the side frame, the said rear

cross tube being positioned between the rear legs of the side frames and welded thereto at the same level as the adjacent point of joinder of the support tube with the rear legs of the said side frames, an intermediate cross tube, said intermediate cross tube being positioned between the said front and rear cross tubes and reaching between and being welded to the said support tubes of the side frames, a seat, said seat having a tubular frame, a series of upwardly curved and spaced apart springs carried by said frame, and seat padding supported on said springs, and upholstering material covering said padding and seat frame, said seat frame resting on and being supported by the said front and intermediate cross tubes, and means for detachably attaching said seat frame to the said front and intermediate cross tubes, a chair back, said chair back being pivotally carried by the chair frame and by the said intermediate cross tube, and means for holding the chair back in adjusted tilted position.

2. In an aircraft passenger chair of the kind described; the structure as defined in claim 1, said chair back having a tubular inverted U-shaped frame said tubular U-shaped frame being positioned between the said side frames of the chair, the lower ends of the legs of the tubular U-shaped frame being pivotally carried between mountings on the chair frame and the said intermediate cross tube to form the aforesaid pivotal mounting of the chair back, a pair of tubular chair back cross frame members, one of said tubular chair back cross frame members being positioned between and adjacent the lower ends of the legs of the tubular U-shaped back frame and welded thereto, the second of the said pair of tubular chair back cross frame members being positioned a short distance below the top and between the legs of the inverted tubular chair back frame and being welded thereto, a series of vertically disposed spaced apart chair back spring elements, said chair back spring elements being welded to the said top and tubular chair back cross members and curving forwardly between the cross members of the chair back, a second tubular chair back frame element, said second tubular chair back frame element being in registry with and spaced behind the first said chair back frame element, and spaced means between and welded to the two chair back frames for holding the frames in their relative positions, said chair back springs having a padding thereover and an upholstery material covering the padding and chair back frames.

3. In an aircraft passenger chair of the kind described; the structure as defined in claim 1, said chair being convertible into a rocking chair, by means of rocker elements that are detachably attached to the base members of the side frames of the chair as shown and described.

MAX T. BLUE.
